O. K. TILLMAN.

LOCK.

APPLICATION FILED AUG. 9, 1917.

1,264,225.

Patented Apr. 30, 1918.

Fl. 10. 1

Fig. 2.

A 3D perspective view of a mechanical assembly. The main body is a rectangular block with various cutouts and a central slot. A long, thin metal strip, labeled 63, is inserted into the slot. A curved metal piece, labeled 66, is attached to the top of the main body. A small rectangular component, labeled 60, is positioned within the central slot. The assembly is labeled 'FIG. 3.' in the top left corner. Other labels visible include 51, 62, 65, 55, 59, 68, 69, 53, 50, 67, and 'OK.Till' in the bottom right corner.

Attorneys

UNITED STATES PATENT OFFICE.

ORION K. TILLMAN, OF HORNER, WEST VIRGINIA.

LOCK.

1,264,225.

Specification of Letters Patent. Patented Apr. 30, 1918.

Original application filed June 8, 1917, Serial No. 173,589. Divided and this application filed August 9, 1917.
Serial No. 185,321.

To all whom it may concern:

Be it known that I, ORION K. TILLMAN, a citizen of the United States, residing at Horner, in the county of Lewis and State 5 of West Virginia, have invented certain new and useful Improvements in Locks, of which the following is a specification.

This invention relates to locks, the present application being a division of an application filed by me June 8, 1917, Serial 10 No. 173,589.

In the accompanying drawings:

Figure 1 is an elevation of the lock, with the side of the casing removed,

Fig. 2 is a vertical section on the line 15 2-2 of Fig. 1,

Fig. 3 is a detail perspective view of the bolt and the tumblers coöperating therewith, this figure showing the side of the 20 bolt opposite that appearing in Fig. 1.

The numeral 1 indicates a portion of a door having a mortise 2 therein which is covered by a mortise plate 3. The lock casing 4 is fitted within the mortise and 25 in the upper portion of the casing is a latch 11 constructed with a tongue 12 to project through the casing and engage the lock strike. The latch is constructed with an elongated opening 14 in order to slide 30 past the hub 6 and the knob spindle 5, said hub having a tooth 9 to engage a notch 10 in the wall of the said opening. A spring 17 bears upon the latch and tends to hold it projected and below the latch is a gravity 35 dog 20 mounted upon a stud pivot 21 and having a tooth 22 to engage a notch in the lower edge of the latch to aid in holding it projected.

A partition 49 is provided within the lock 40 case 4 below the gravity dog 20 and is shaped, as shown clearly in Fig. 1, to receive the lower forward corner of said dog when the same is in its lowest position. Below the said partition, the key bolt 50 is 45 slidably mounted in the lock case and rests upon the lower wall of said case, said wall being inclined rearwardly, as shown at 51, so that the bolt will tend to remain in a retracted position under the influence of 50 gravity. A dust escape opening 52 is provided through the lower wall or end of the lock case so as to permit the escape of any dirt or dust that may accumulate therein. The bolt is constructed near its rear end 55 with a transverse shoulder 53 adapted to

engage a projection 54 on the inner wall of the lock case and be thereby limited in its retracting movement, and a transverse shoulder 55 is provided on the under side or edge of the bolt to engage a shoulder 56 60 on the lower wall of the lock case and thereby limit the projecting movement of the bolt. The projecting movement of the bolt is further limited by the transverse shoulder 57 at the top of the bolt near the front end 65 thereof, and a web 58 extends longitudinally of the bolt from the front end thereof to the rear end, the said web being of less width than the bolt so that a space is provided at each side of the web in which the 70 wards of a key may play. A transverse opening 59 is formed through the bolt and the said web 58 and the upper wall of this opening is defined by a substantially inverted V-shaped notch 60 formed in the 75 lower edge of the web. On one side of the bolt, I form a step 61 which is adapted to be engaged by the reduced front end 62 of a tumbler 63 which is pivoted at its inner or rear end upon the side of the partition 49, 80 and a spring 64 may be secured upon the partition so as to bear upon the upper edge of said tumbler and insure its engagement with the bolt at all times. When the bolt is retracted, as shown in Fig. 1, the reduced 85 end of the tumbler fits over the step 61 and rests upon the upper or tread surface of the step. When, however, the bolt is projected, the extremity of the tumbler drops into engagement with the riser portion of 90 the step and thereby serves to prevent retraction of the bolt. On the opposite side of the bolt, a ledge 65 is provided at the side of the web 58 and a tooth or spur 66 is located on this ledge between the ends 95 of the same. A tumbler 67 is pivoted at its inner rear end on the side of the partition 49 and the free end of this tumbler is constructed with a notch 68 and a hook or bill 69. When the bolt is retracted, the 100 tooth or spur 66 will be engaged in the notch 68 and will, consequently, be held against movement in either direction. When a proper key, however, has been inserted and manipulated, the bolt will be 105 projected and the hook or bill 69 will drop behind the lug, tooth or spur 66 and will, consequently, aid the tumbler 63 in holding the bolt projected so that the door will be held locked. The key to release the lock 110

will, of course, be fitted to the dimensions of the tumblers and the wall of the notch 60 in the bolt, and slight variations in the proportions of these parts will render any 5 particular lock inoperative to any key except the one fitted especially to it. The key will be constructed with a notched wing so that when it is inserted through the key-hole 70 and turned the notched edge of the 10 wing will ride upon the rear wall of the notch 60 and will engage the front wall of the same so as to exert a push upon the bolt through the web 58. The edges of the wing at the sides of the notch will bear against 15 the under edges of the respective tumblers and will release the same so that the bolt may be projected, and continued movement of the key will, of course, release the tumblers so that they will drop into engagement 20 with the bolt to hold it in the locked position. Rotation of the key in the opposite direction will first release the tumblers from the bolt and will then ride against the wall of the notch in the web so as to retract the 25 bolt, as will be readily understood.

Having thus described the invention, what is claimed as new is:

Copies of this patent may be obtained for five cents each, by addressing the "Commissioner of Patents, Washington, D. C."

1. In a lock, the combination of a slidably mounted gravitating bolt having a central longitudinal web provided with a substantially V-shaped notch in its lower edge, a step on one side of the bolt, and a tumbler pivotally mounted above the bolt and having a reduced end adapted to rest on said step in one position of the bolt and engage against the step in another position of the bolt. 30

2. In a lock, the combination of a slidably mounted gravity bolt, a tooth on one side of the bolt, and a tumbler pivotally mounted 40 above the bolt and constructed at its end to engage over or against the inner side of said tooth.

3. In a lock, the combination of a lock casing having an inclined lower wall and 45 provided with spaced vertical shoulders on said wall, and a bolt slidably mounted on said wall and provided on its lower edge with stops adapted to engage said shoulders whereby the retracting and projecting 50 movement of the bolt will be limited.

In testimony whereof I affix my signature.

ORION K. TILLMAN. [L. S.]
